ROUTER

Daniel C. Green, Scranton, Pa., assignor to Wesel
Manufacturing Company, Scranton, Pa.

Application March 28, 1947, Serial No. 137,993

Term of patent 14 years

(Cl. D93—2)

To all whom it may concern:

Be it known that I, Daniel C. Green, a citizen of the United States, residing at Scranton, in the county of Lackawanna and State of Pennsylvania, have invented a new, original, and ornamental Design for Router, of which the following is a specification, reference being had to the accompanying drawing, forming part thereof.

Figure 1 is a perspective view of a router, showing my new design.

Fig. 2 is a rear view of the router shown in Figure 1; and

Fig. 3 is a top plan view of the router shown in Figure 1.

I claim:

The ornamental design for a router, as shown.
DANIEL C. GREEN.
